UNITED STATES PATENT OFFICE.

JULIUS JASPER, OF NEW YORK, N. Y., ASSIGNOR TO THE J. HENRY PETERS COMPANY, OF SAME PLACE.

DESIGN FOR A SKIRT-BINDING.

SPECIFICATION forming part of Design No. 34,299, dated March 26, 1901.

Application filed February 26, 1901. Serial No. 49,002. Term of patent 7 years.

To all whom it may concern:

Be it known that I, JULIUS JASPER, a citizen of the United States, and a resident of the borough of Manhattan, in the city and State of New York, have invented a new and original Design for a Skirt-Binding, of which the following is a specification.

The essential feature of my design consists in the skirt-binding having a brush pendent from one edge thereof, the heading presenting a series of short columns in proximity to the brush, a series of longer columns separated from the series of short columns by a cord-line, the series of longer columns being alternately more and less pronounced.

In the accompanying drawing, which represents a view of a piece of the skirt-binding,

the brush is denoted by *a*, the series of short columns in proximity thereto by *b*, the series of longer columns by *c* and *d*, *c* representing the more pronounced and *d* the less pronounced columns, and *e* represents the cord-line separating the two series of columns.

What I claim is—

The design for a skirt-binding, substantially as herein shown and described.

In testimony that I claim the foregoing as my invention I have signed my name, in presence of two witnesses, this 20th day of February, 1901.

JULIUS JASPER.
